ELECTRON DISCHARGE DEVICE

Filed April 18, 1919

INVENTOR
WILLIAM A. KNOOP
BY *Jed C.R. Palmer* ATTORNEY

UNITED STATES PATENT OFFICE.

WILLIAM A. KNOOP, OF BROOKLYN, NEW YORK, ASSIGNOR TO WESTERN ELECTRIC COMPANY, INCORPORATED, OF NEW YORK, N. Y., A CORPORATION OF NEW YORK.

ELECTRON-DISCHARGE DEVICE.

Application filed April 18, 1919. Serial No. 290,968.

This invention relates to vacuum tubes of the three-electrode type known as the audion.

Its object is to provide an improved self-supported electrode assembly whereby the use of a glass arbor or cane is obviated.

In accordance with this invention the anode is made up of a pair of parallel plates anchored in the press and spaced apart at their ends by blocks of insulation secured thereto, the cathode and grid being located between the anode plates and supported at their opposite ends by said blocks.

Referring to the drawing 11 designates a vacuum tube 11 having a press 12, and a double surface plate electrode 13 mounted on said press 12 at its lower end by rigid wires 14, and spaced at its lower and upper ends by the insulating spacers, preferably of

“lavite” 15, 16 and 17. These spacers comprise flat slabs of “lavite”. The plate surfaces are connected metallically by wire rivets 18 at the bottom and by wires 19 and 20 at the top, which are at points welded to

the plate structure. The ends of wires 19 and 20 are brought together at the top in a point 21 which projects into the top of the vessel 11 and may provide means whereby too much vibration of the electrode unit is

prevented. A grid 22 rests on the lower “lavite” spacer and is connected to a rigid lead-in wire 23 and is guided at its top by sliding in grooves 24 in the sides of the spacers 16 and 17. Wires 25 and 26 are connected to the spacers 16 and 17 and are provided at their free ends with loops through which passes a filament 27 which is connected at its lower ends to wires 28 on the spacer 15 and a lead in wire 29. It

is apparent that by this structure an electrode unit is provided in which a double surface electrode, mounted on an audion press, is spaced by insulating material and, through the insulating material, serves as a support for another electrode.

What is claimed is:

1. An electron discharge device comprising opposed parallel anode plates, insulating blocks carried thereby at opposite ends thereof, and a cathode and a double grid electrode located between the anode plates and supported at their opposite ends by said blocks.

2. An electron discharge device comprising opposed anode plates, insulating blocks carried thereby at opposite ends thereof, a cathode, and a double grid electrode located between the anode plates and supported at their opposite ends by said blocks, a press and metallic means for supporting the anode plates from said press.

3. An electron discharge device comprising a vessel containing an anode, and another electrode, and means for supporting both electrodes as a unit from the same end of said vessel, the anode comprising two opposed portions having continuous surfaces, said means comprising insulating connecting members for spacing one portion from the other portion and comprising additional means for supporting said portions from the vessel wall.

4. An evacuated vessel having a press and containing an anode, a grid having an end adjacent the press, and means carried by the anode for supporting the end of the grid adjacent the press.

5. An evacuated vessel having a press and containing an anode, a grid, and a cathode, each having an end adjacent the press, and means carried by the anode for supporting the ends of the cathode and the grid adjacent the press.

6. An electron discharge device comprising a vessel having a stem, an electrode structure comprising two parallel plates having continuous surfaces, insulating means for spacing one of said plates from the other, metallic means for supporting said plates solely from said stem, and an electrode supported from said insulating means.

7. An electron discharge device comprising a vessel having a press, an anode comprising a pair of parallel plates supported solely from said press, spacing means for said plates comprising a block of insulating material interposed between said plates and supported thereby, and a plurality of electrodes supported by the said insulating spacing means.

8. An electron discharge device comprising an evacuated vessel, an anode, a cathode and a grid, means for supporting the cathode and the grid by the anode at one end of said vessel, and means for supporting the

anode, the cathode, and the grid, as a unit at the other end of said vessel.

9. An electron discharge device comprising an anode, an insulating block supported by said anode, said block having grooves, and a grid having portions arranged to slide in said grooves.

10. An electron discharge device comprising an insulating block having grooves and an electrode having portions slidably arranged in said grooves. ¹⁰

In witness whereof, I hereunto subscribe my name this 15th day of April A. D., 1919.

WILLIAM A. KNOOP.
